United States Patent Office.

LOUIS VERSTRAET, OF PARIS, FRANCE.

Letters Patent No. 85,877, dated January 12, 1869.

IMPROVEMENT IN HYDROCARBON-BURNERS.

The Schedule referred to in these Letters Patent and making part of the same.

To all whom it may concern:

Be it known that I, LOUIS VERSTRAET, of Paris, in the French Empire, chemist, have invented certain new and useful Improvements in Apparatus for the Direct Combustion of Petroleum and any other mineral oils, for the purpose of heating steam-boilers and other industrial or domestic fire-places; and I do hereby declare that the following is a full, clear, and exact description of the same, reference being had to the annexed sheet of drawings, making a part of the same.

My invention refers to an apparatus for the direct combustion of any petroleum and other mineral oils, for the purpose of heating steam-boilers and other industrial and domestic fire-places.

In a former application for Letters Patent, I claimed certain improvements in the processes and apparatus for storing up and burning in safety petroleum and any other mineral oils, for the above-expressed purposes. I specified that I burned these oils in a semi-cylindrical capsule, lined with fire-bricks, and that I employed, for dividing the gases and preventing any carrying up of the oils through the chimney, either pumice-stone or any other divisible body; that I caused the coming of the liquid under the cylinder, and regulated the flow by a Mariotte tube.

By this present application, I claim a special apparatus, burning the oils in a single jet, by spreading them in a sheet on the furnace.

The object of this apparatus is to render both easy and regular the feed of the fuel, and to supply the oils with the necessary air to a complete oxidation.

I have represented some specimens of my improved apparatus in the accompanying drawings, wherein—

Figures 1, 2, 3, 4, and 5, show various views of the apparatus.

Figure 6 shows, in vertical sectional elevation through A B, fig. 7, my apparatus applied to heating a fire-place for a small steam-boiler, of Belleville's system.

Figure 7 shows a sectional plan of the same fire-place, provided with the apparatus through C D, fig. 6.

In all these figures the same letters of reference indicate the like parts.

My apparatus is composed of—

First, of a feed-pipe, shown in plan, fig. 1, of the annexed drawing, and in vertical section, fig. 2.

This flat pipe, which may be made of iron or cast-iron, consists of three parts.

The first, A B C D, constitutes the reservoir.

The second, X X, is a movable lid, to be bolted on an angle-iron, a b c d, figs. 1 and 2, inside the reservoir A B C D. This piece is cast with three waste-tubes E E E, figs. 1 and 2, plunging into the oil up to two-fifths of an inch of the bottom of the reservoir.

The fore portion of the apparatus is inclined toward the fire-place, as shown by the section F, fig. 2.

The oils come in through the tube G, and run out more or less rapidly through the pipes E E E, accord-

ing to the pressure existing in the main oil-reservoir, and also according to the requirements of the service.

And to cover the parts X F, which I have just described, I dispose a lid, provided likewise longitudinally with an inclined plane, I I, leaving only one-fifth of an inch of vacuum between that part and the part J, also inclined, and cast with the pipes E E E.

The whole length of the reservoir, for an ordinary furnace, is twenty-six inches, its breadth four, and its height from two to four inches, so as to contain from one to one and a half gallon of oil.

Secondly. The second piece of this apparatus is composed of a cast-iron cascade, represented, at fig. 3, in horizontal section, through E F of fig. 5; at fig. 4, in vertical section, through A B, fig. 3; and at fig. 5, in front sectional view, through C D of fig. 4.

This apparatus consists of a square case or box, O, with two of its sides, N P, open.

It has in its lower bottom a large pipe, M M, intended to receive, from any suitable blower, either atmospheric air, or the air which, having gone through the oil-reservoir, has become saturated with the light vapors from these oils.

During the work of the blower, the open portion N of the apparatus is closed by a slide, shown at fig. 6, opening or shutting access to the air in the furnace.

The slide is wide opened, so as to supply atmospheric air to the fire-place when the blower is stopped.

The second half of this case, or the portion toward the fire-place, and which takes rise at P, is composed of four superposed plates, R R' R'' R''', separate from one another by from four-fifths to one and three-fifths inch, inclined toward the fire-place, and supported by brackets S S S S, fig. 5, cast with the plates R.

The plates thus form a cascade, which divides the oils in one large, thin sheet, and brings them, burned partly, to the main furnace, provided with the divisible body.

The oils flow out through the pipes E E E, figs. 1 and 2, drop on the first plate R, figs. 4 and 5, rush afterward on the second plate R', then on the third, R'', and finally on the fourth, R''', thence to fall into the fire-place, furnished with pumice-stone, Z, fig. 6, where they are entirely consumed.

From this arrangement results the great advantage of regulating at will, by means of one stop-cock only for each fire-place, the run of the oils, and I supply largely the air necessary to their combustion, yet preventing their being carried off by too violent a current of air.

Further, the air from the blower is broken and divided against the sides of the case, figs. 3, 4, and 5, before its contact with the oils, and it is thus uniformly distributed in all the parts of the fire-place.

I obtain, by means of this arrangement, the carrying to the fire-place of all the gases and light vapors emitted by the oils.

Claims.

The apparatus, described and shown, for the direct combustion of the petroleum and any other mineral oils, for the purpose of heating steam-boilers and industrial and domestic fire-places, the said apparatus being characterized by the combination of the box or case A B C D and the plates R R' R'' R''', disposed as a cascade, for the purposes of throwing or spreading

the oils in a sheet on the fire-place, by means of a single jet, and of supplying largely the air which is necessary to their combustion, as herein shown and described.

L.S. VERSTRAET.
